[57] CLAIM

The ornamental design for a microscope, substantially
as shown and described.

DESCRIPTION

FIG. 1 is a perspective view of a microscope, taken
from the right front thereof showing our new design;
FIG. 2 is a perspective view of the microscope of FIG.
1 taken from the left rear thereof; and
FIG. 3 is a side elevational view of the microscope of
FIGS. 1 and 2 showing the eyepiece in a rotated pos-
ition.

FIG. 1

FIG. 2

FIG. 3
